UNITED STATES PATENT OFFICE.

CHARLES J. TRAVERS, OF PORT WASHINGTON, WISCONSIN, ASSIGNOR TO GILSON MANUFACTURING CO., A CORPORATION OF WISCONSIN.

CHAIR-IRON.

1,263,156.

Specification of Letters Patent.

Patented Apr. 16, 1918.

Application filed August 4, 1917. Serial No. 184,395.

To all whom it may concern:

Be it known that I, CHARLES J. TRAVERS, a citizen of the United States, residing at Port Washington, in the county of Ozaukee 5 and State of Wisconsin, have invented a new and useful Chair-Iron, of which the following is a specification.

This invention relates to improvements in chair-irons employed in revolving chairs, 10 and the objects and advantages of the invention will hereinafter appear and be particularly pointed out in the claims.

Referring to the drawings:

Figure 1 is a vertical longitudinal sectional view of a chair-iron embodying my invention, the legs being broken away;

Fig. 2 is a horizontal sectional view of the same, the section being taken on the line 2 2 of Fig. 1 looking in the direction of 20 the arrows;

Fig. 3 is a detail in plan of the bottom leg-plate.

Similar numerals of reference indicate similar parts in all the figures of the drawings.

In the typification of my invention as illustrated in the drawings, 1, designates the hub of the iron, and the same may be externally cylindrical, as herein shown, or of 30 any other shape desired. This hub is preferably of cast-metal, as is usual, and provided with a central longitudinal bore 2, extending throughout the same, and terminates at its upper end in an annular flange 3, at one point of the edge of which is integrally formed a short vertical standard 4, transversely perforated and threaded, as at 5, for a stop-screw 6, the inner end of which extends inwardly beyond the stand- 40 ard.

At diametrically opposite points, the hub may be formed with integrally formed radial studs 7, the same being located at the points at which the inner ends of the 45 legs of the chair abut and between upper and lower annular bosses, 8 and 9, respectively formed on the exterior of the hub.

Mounted to revolve within the bore 2 of the hub, is the usual adjusting-standard or 50 screw 10, provided with the usual longitudinal groove 11, which in this instance, extends from the upper end of the screw to a point near the lower end thereof. The lower end of the screw is preferably left 55 plain or unthreaded, as at 12, so that in re-

volving it will not have a tendency to cut the interior of the bore 2. Also, by terminating the slot or groove 11 above the lower end of the screw, the hand-wheel and what is generally termed the "J-washer," cannot 60 work from their positions on the screw during shipment.

Fitting the boss 8 of the hub and positioned immediately below the annular flange 3 of the same, is the upper leg-plate 13, 65 which is preferably of concavo-convex form and provided with screw-holes 14, coincident with the legs of the chair-base.

Fitting the lower boss 9, is the lower leg-plate 15, (see Fig. 3), and the same con- 70 sists of an annular central ring 16, and radial arms 17, corresponding with the position and curvature of the undersides of the legs.

18 designates the wooden legs, there be- 75 ing the usual number—four—and said legs are of the usual design. In this instance, the inner ends of the legs are slightly curved, so as to conform to the exterior of the hub, but in any instance may be changed 80 to agree therewith, and they are further provided with pairs of shallow cavities 19, (see dotted lines Fig. 2) to receive the studs 7. It will be obvious that the studs may be omitted, if desired, and also the openings 85 or cavities 19 for receiving them, and also that any other form of projection desired may be formed on the hub and correspondingly shaped cavities formed in the ends 90 of the legs.

The corners of the legs are preferably cut away, as at 20, and between each pair of legs is positioned a somewhat triangularly shaped filler-block 21, the inner edge of which is formed with an angular exten- 95 sion 22, adapted to snugly fit between the cut away portions 20 of the adjacent legs and abut against the two bosses 8 and 9 in the same manner as do the inner ends of the legs. Thus, it will be seen, that the legs 100 and blocks combine to complete the circle about the hub 1.

Numerous means may be substituted for those shown for the purpose of securing the legs, their upper and lower plates 13 105 and 15 and the filler-blocks in position, and I do not wish to be understood as limiting my invention in this respect. In the present instance, however, I punch inwardly disposed tongues 23, preferably two, from each 110

of the arms 17 of the lower leg-plate, each tongue being preferably perforated or provided with a screw-hole 24. Between the arms 17, the annular portion of the lower leg-plate may be provided with a nail-hole 25.

The undersides of the legs 18, are provided with shallow cavities 26, having abrupt shoulders 26^a at their inner end to receive and engage the free ends of the tongues 23, the relative positions of the cavities and tongues being such that when the latter are within the former the legs are forced snugly against the hub. When thus positioned, it will be seen that the legs are clamped between the upper and lower leg-plates 13 and 15, after which screws 27, are inserted downwardly through the screw-holes 14 of the upper leg-plate 13, and screws 28, are inserted upwardly into the undersides of the legs through the holes 24 of the tongues 23, these means preferably being supplemented by the stud or tenons 7 entering the cavities 19.

25 After the legs have been positioned and secured the intermediate filler-blocks are inclined and inserted under the concavo-convex upper leg-plate 13, and subsequently forced upward and inward, thus bringing them into a vertical position and snug fit with the sides of the legs 18, lateral movement of the blocks at their upper ends being prevented by the depending edge of the upper leg-plate engaging the same. Nails 39, (see dotted lines Fig. 2) are then driven upwardly through the perforations or nail-holes 25 in the bottom leg-plate and into the filler-blocks, whereby the latter when once positioned are prevented from lateral displacement.

40 This completes the description of my invention in detail and it only remains to mention the fact that in the present instance, there is mounted on the screw or adjusting-standard 10, immediately above the flange 3 of the hub 1, the usual J-washer 29, which, by means of a spline 30, that engages the groove 11 of said screw or adjusting-standard, is nonrotatably yet slidably mounted upon the latter. This J-washer is of the well-known construction—its upper side being provided with shallow radial ribs lightly engaging with corresponding grooves formed in the underside of the hub 31, of the usual hand-wheel 32, the said hub being countersunk on its underside to receive the washer. To prevent the separation of hub, hand-wheel and J-washer, the hub is provided with an external annular flange 33, over which engages the beforementioned screw 6. The hand-wheel is threaded on the screw or adjusting-standard, and by rotating the same, it will be obvious, the hand-wheel being held down by the screw 6, the screw or adjusting-standard will be fed up or down

and thus raise or lower the chair, the latter, it being understood, being supported by the usual means at the upper end of the screw or adjusting-standard. On the other hand, it will be seen that as the occupant revolves the 70 chair, and, consequently the screw or adjusting-standard, the hand-wheel and J-washer will revolve together, the latter bearing on the upper side of the annular flange 3 of the hub 1. If desired, antifriction devices of any well known character may be inserted between the underside of the J-washer and the upper side of the flange 3, such forming no part of my invention.

The filler-blocks, it will be observed more 80 particularly by reference to Fig. 1 of the drawing, are greater in length, vertically considered, than are the legs of the chair-base, and, for this reason, when their bottoms rest upon the lower plate 15, their 85 upper ends will be above the legs and therefore in engagement with the depending flange of the plate 13. The flange of the latter, therefore, coacts with the nails 39 to retain the filler-blocks in position, the flange 90 obstructing any lateral movement of the blocks when they are once positioned.

Having described my invention, what I claim is:

1. In a chair-iron, the combination with a 95 bored hub, and legs radiating therefrom, of upper and lower plates exterior of the hub and between which the legs are located and secured, the upper plate being of concavo-convex shape in cross section, and filler-blocks located between the legs and having their upper ends engaging the depending edge of the upper plate.

2. In a chair-iron, the combination with a bored hub, and legs radiating therefrom, 105 of upper and lower plates located upon the hub and embracing the legs at their upper and lower sides, the upper plate having a depending flange, means for securing the legs between the plates, and filler-blocks positioned between the legs and plates, said blocks having their upper ends extending above the legs and engaging the flanges of the upper plate.

3. In a chair-iron, the combination with 115 a bored hub, and legs radiating therefrom, said legs having their inner ends shaped to conform to and abutting against the hub and their inner vertical corners beveled, of upper and lower plates secured upon the hub and 120 embracing the legs at their upper and lower sides, the upper plate having a depending peripheral inclined flange, means for securing the legs between the plates, and filler-blocks positioned between the legs and the 125 plates, said blocks having their inner edges shaped to conform to the inner beveled vertical edges of the legs and having their upper ends extending above the legs and their outer corners beveled and engaged by 130

the inclined peripheral flange of the upper plate.

4. In a chair-iron, the combination with a bored hub provided at its upper end with a radial flange and below the same with radial studs, and legs having their inner ends provided with holes to receive said studs, said legs radiating from the hub, of upper and lower plates embracing the upper and lower sides of said legs, the upper plate having a

peripheral flange, filler-blocks positioned between the legs and plates and having their upper ends engaged by said flange of the upper plate, and securing means between the plates and the legs.

CHARLES J. TRAVERS.
